UNITED STATES PATENT OFFICE.

JOHN SALMINEN, OF BROOKLYN, NEW YORK.

APPARATUS FOR RESEATING VALVE-BODY SEATS.

1,355,700.

Specification of Letters Patent. Patented Oct. 12, 1920.

Application filed August 2, 1919. Serial No. 314,993.

To all whom it may concern:

Be it known that I, JOHN SALMINEN, a citizen of the United States, residing in Brooklyn, in the county of Kings and State of New York, have invented certain new and useful Improvements in Apparatus for Reseating Valve-Body Seats, of which the following is a specification.

This invention relates to apparatus for seating valve body seats of gate valves; and has for an object to provide an apparatus of this kind adapted to reseat the valve body seats of valves from which the valve cap and stem have been removed but which are still connected to the pipe line.

Other objects of the invention are to provide an apparatus adapted to be easily mounted upon the flange of the valve barrel and to provide an apparatus of this kind in which the reseating tool may be fed either automatically or by hand.

Other objects are to provide an apparatus of this kind which will be efficient and durable in operation, which may be economically manufactured, and which will not get out of order.

Other objects of the invention will appear as the description proceeds; and while herein minute details of the invention are described, the invention is not limited to these, since many and various changes may be made without departing from the scope of the invention as claimed.

In the accompanying drawing forming by way of example one of many possible embodiments of the invention—

Figure 1 is a side elevation of my improved apparatus shown applied to a valve barrel, the valve barrel and body-seat being shown in the vertical section;

Fig. 2 is a fragmental end elevation of the lower part of the apparatus;

Fig. 3 is a plan partly in horizontal section taken on the line 3—3 of Fig. 1;

Fig. 4 is a fragmental vertical sectional view, on an enlarged scale, of the lower end of the apparatus;

Fig. 5 is a horizontal sectional view taken on the line 5—5 of Fig. 4, and

Fig. 6 is a side elevation, on a larger scale, of the upper end of the apparatus.

My improved reseating apparatus is shown as applied for reseating the valve body seat 10 of a gate valve, from the valve barrel 11 of which the valve cap and valve stem have been removed.

The apparatus is supported on an H-shaped base 13 having supporting arms 14 resting upon and adapted to be clamped upon the flange 16 of the valve barrel. Said base is provided with a vertical body portion 18 formed with a flat vertical slide-way 19 having an under-cut beveled fixed guide 20 at one edge. At the other edge of the slide-way there is provided an under-cut beveled adjusting gib 23 held in place by a headed bolt 24 engaging in said body portion 18.

The operating mechanisms of the apparatus are mounted upon an adjustable support 25 comprising a vertical, beveled slide 26 held in said slideway by said guide 20 and said gib; and upon said support are formed upper bearing brackets 27 and 28 having respectively vertical and horizontal upper bearing bores 30 and 31. At the lower part of said support are lower vertical and horizontal bearing brackets 33 and 34 having respectively vertical and horizontal lower bearing bores 35 and 36, said horizontal bracket 34 being provided with an external annular seat 38 (Fig. 4) around its inner end and an annular recess 39 around the outer end of its bearing bore 36.

A rotary sleeve 42 mounted in said vertical bores 30 and 35 is provided with a series of vertical holes 43 (Fig. 6) in its upper end; and an upper driven bevel gear 45 is fixed on said sleeve above said upper bearing bore 30 and is engaged by a driving gear 46 mounted on a drive shaft 47 mounted in said upper horizontal bore 31, and connected to any suitable drive means or source of power not shown.

A feed shaft 50 is disposed in said sleeve 42 and projects at both ends of the sleeve, and is provided with a hand wheel 51 fixed on its upper end and resting on said sleeve. Said wheel is provided with a handle 54 and with a small bore 55 adapted to register with any one of said holes 43. A locking pin 56 in said small bore 55 may rest in any one of said holes 43, whereby the sleeve 42 and feed shaft 50 may be locked together at will.

A journal shaft 60 is rotatably mounted in said lower horizontal bearing bore 36 and is held in place by a retaining plate 61 secured to the outer end of the journal shaft and received in said annular recess 39. A supporting gear 64 formed on and integral with the inner end of said journal shaft is

provided with peripheral bevel-gear teeth 65, a diametric feed-screw receiving bore 66, a diametric under-cut guide-way 67 and an elongated guide recess 68 in the bottom of 5 said under-cut recess and communicating with said feed-screw receiving bore. A feed screw 70 is provided in said screw-receiving bore 66 and has thereon a driven feed pinion 71 disposed in a pinion receiving recess 72 10 formed in said supporting gear.

A tool carrier 74 is slidable in said under-cut guide way 67 and is provided with an elongated lateral extension 75 disposed in 15 said guide recess 68 and has thread segments 76 engaging said feed screw. A compensating gib 77 in one side of said guide way prevents lateral play of the tool carrier.

A tool head 80 is formed on the end of 20 said tool carrier and is provided with a diagonal tool-seat opening 81 provided in one wall thereof with a longitudinal screw receiving recess 82. In said opening is disposed a tool block 85 provided with interrupted threads 86 and with a tool-receiving 25 recess 87 receiving a tool 88 against a shoulder 89 at the rear of the recess. A clamping screw 92 in said head holds the tool in place and presses it against said block. An adjusting screw 94 in said screw-receiving 30 recess 87 engages said threads 86 and serves for adjusting the block when the adjusting screw is rotated by a suitable tool. Said screw 94 is held against longitudinal movement by the heads 95 and 96, one, for instance the head 96, is adapted to receive a 35 wrench for adjusting the tool block.

A drive pinion 97 on said sleeve 42 engages the teeth of said supporting gear 64 and drives the supporting gear when the 40 shaft 47 is rotated. A double idler gear 98 is rotatable on said seat 38 of the bearing bracket 34 and engages said feed pinion 71; and a feed drive gear 100 on said feed shaft 50 engages said idler gear 98, thereby 45 rotating the feed screw and feeding the tool carrier when the feed shaft 50 is rotated.

The teeth of said supporting gear 64, said 50 drive pinion 97, said feed pinion 71, said idler gear 98, and said feed drive gear 100 have such ratios that the feed screw will feed out when said sleeve 42 and feed shaft 50 are locked together, by the pin 56, and rotated.

The operation of the device will be readily 55 understood from the foregoing description and need now be described only briefly as follows:

The valve cap and stem being removed, the base 13 is placed upon the flange of the 60 valve barrel, and the bolt 24 loosened sufficiently to permit the supporting member 25 to be adjusted until the axis of the journal shaft 60 is placed in alinement with the valve body seat after which the bolt 24 is 65 tightened to lock the member 25. The pin

56 is then withdrawn and the handle 54 revolved until the tool 88 is withdrawn to within the valve body seat, whereupon the apparatus is moved toward the valve seat to a position for taking a light cut from the 70 seat. The base 13 is then clamped in place by suitable clamps, and the shaft 48 rotated and the tool revolved until it is seen that the proper alinement has been made. Power is then applied and the tool revolved and 75 gradually fed outward, thus taking a light cut from the seat.

This outward feeding may be made by manual operation of the hand wheel 51 or it may be accomplished automatically 80 merely by locking the feed shaft and drive sleeve together by means of the pin 56, the difference in the ratios of the several operating gears causing a gradual feeding out of the tool carrier as the apparatus is rotated forwardly.

After the first cut has been made the pin 60 is withdrawn and the tool is carried back to its initial position on the supporting member 64 by manual operation of the wheel 90 51. The screw 92 is then loosened and the tool block 85 fed out a small amount by manipulating the adjusting screw 94. Another cut may then be taken from the valve body seat, and the operation repeated until 95 the desired reseating has been effected.

I claim:

1. In combination, a support; a rotary sleeve mounted on said support and provided with a series of holes in its outer end; 100 means for rotating said sleeve; a feed shaft in said sleeve; a hand wheel fixed on said feed shaft and provided with a small bore adapted to register with any one of said holes; a locking pin in said small bore and engaging in one of said holes; a supporting gear mounted on said support; a feed screw disposed across said supporting gear; a tool carrier disposed across said supporting gear and movable by said screw; gear means operatively connecting said supporting gear and sleeve; and gear means operatively connecting said shaft and feed screw. 110

2. In an apparatus for reseating valve body seats, the combination of a support 115 adapted to be secured to the flange of a valve barrel; a rotary sleeve vertically mounted on said support and provided with a series of vertical holes in its upper end; an upper driven bevel gear fixed on the upper end of said sleeve; a drive shaft; an upper driving bevel gear on said drive shaft and engaging 120 said driven gear; a feed shaft in said sleeve and projecting at both ends; a hand wheel fixed on the upper end of said feed shaft and resting on said sleeve and provided with a handle and with a small bore adapted to register with any one of said holes; a locking pin in said small bore and resting 125 in one of said holes; a supporting gear 130

mounted on said support; a feed screw disposed across said supporting gear; a tool carrier disposed across said supporting gear and movable by said screw; gear means operatively connecting said supporting gear and sleeve; and gear means operatively connecting said shaft and feed screw, and having such ratio that said feed screw is caused to feed when the sleeve and feed shaft are 10 locked together and rotated.

3. In combination, a support, a rotary member mounted on said support; a rotary feed member on said support; means for locking said members together; a supporting member rotatably mounted on said support and operatively connected to said rotary member; a feed screw on said supporting member; a double idler gear rotatable on said support and operatively connected to 15 said feed screw; and a feed drive gear on said feed member and engaging said idler gear.

4. In combination, a support comprising a bearing bracket having a horizontal bearing bore; a rotary sleeve mounted on said support; a feed shaft in said sleeve; means for locking said shaft and sleeve together; a journal shaft rotatably mounted in said horizontal bearing bore; a supporting gear 20 on the inner end of said journal shaft and having a diametric feed-screw in said receiving bore and having a feed pinion thereon; a tool carrier moved by said feed screw; a drive pinion on said sleeve and engaging 25 the teeth of said supporting gear; an idler gear rotatable on said bracket and engaging said feed pinion; and a feed drive gear on said feed shaft and engaging said idler gear; the teeth of said supporting gear, 30 said drive pinion, said feed pinion, said idler gear, and said feed drive gear having such ratio that the feed screw will feed when said sleeve and feed shaft are locked together and rotated.

5. In an apparatus for reseating valve body seats, the combination of a support comprising a lower horizontal bearing bracket having a horizontal bearing bore, said horizontal bracket being provided with 35 an external annular seat around its inner end and an annular recess around the outer end of its bearing bore; a rotary sleeve mounted on said support; a feed shaft in said sleeve; means for at will locking said shaft and sleeve together; a journal shaft rotatably mounted in said horizontal bearing bore; a retaining plate secured to the outer end of said journal shaft and received in said annular recess, a supporting gear 40 formed on and integral with the inner end of said journal shaft and having a diametric feed-screw receiving bore and a guideway communicating with said bore; a feed screw in said receiving bore; a feed pinion on said screw; a tool carrier on said

supporting gear and moved by said screw; a drive pinion on said sleeve and engaging the teeth of said supporting gear a double idler gear rotatable on said seat and engaging said feed pinion; and a feed drive gear 70 on said feed shaft and engaging said idler gear; the teeth of said supporting gear, said drive pinion, said feed pinion, said idler gear, and said feed drive gear having such ratio that the feed screw will feed 75 when said sleeve and feed shaft are locked together and rotated.

6. In combination, a support; a supporting member rotatably mounted on said support and provided with a transverse guide-way; a transverse feed screw; a tool carrier fitting in said guide way and having thread segments engaging said feed screw; means for rotating the supporting member; and means for rotating the feed screw. 80

7. In combination, a support; a supporting member mounted on said support and provided with a diametric feed screw receiving bore, a diametric under-cut guide-way, and an elongated guide recess in the bottom of said under-cut recess and communicating with said bore; a feed screw in said receiving bore; a tool carrier fitting in said under-cut guide way and provided with an elongated lateral extension disposed in said guide recess and having thread segments engaging said feed screw; means for driving the supporting member; and means for rotating the feed screw. 90

8. In combination, a support; a rotary drive member and a rotary feed member on said support; means for locking said members together; means for rotating said drive member; a supporting gear rotatably mounted on said support and provided with a diametric feed-screw receiving bore, a diametric under-cut guide-way, an elongated guide recess in the bottom of said under-cut recess and communicating with said bore, and a pinion receiving recess; a feed screw in said receiving bore; a driven feed pinion on said screw and disposed in said recess; a tool carrier fitting in said under-cut guide way and provided with an elongated lateral extension disposed in said guide recess and having thread segments engaging said feed screw; gear means operatively connecting said drive member and said supporting gear; and gear means operatively connecting said feed pinion and said feed member. 100

9. In an apparatus for reseating valve body seats, the combination of supports; a rotary sleeve and a rotary feed shaft on said support; means for locking said sleeve and shaft together; means for rotating said sleeve; a supporting gear rotatably mounted on said support and provided with a diametric feed-screw receiving bore, a diametric under-cut guide-way, an elongated guide recess in the bottom of said under-cut recess 105 110 115 120 125 130

- and communicating with said bore, and a pinion receiving recess; a feed screw in said receiving bore; a driven feed pinion on said screw and disposed in said recess; an idler gear on said support and engaging said feed pinion; a tool carrier fitting in said under-cut guide way and provided with an elongated lateral extension disposed in said guide recess and having thread segments 5 engaging said feed screw; a drive pinion on said sleeve and engaging the teeth of said supporting gear and a feed drive gear on said feed shaft and engaging said idler gear and operatively connected with said feed pinion.
10. In an apparatus for reseating the valve body seats of a gate valve from the valve barrel of which the valve cap and valve stem have been removed, the combination of a base having supporting parts adapted to be supported on the barrel, and provided with a body portion formed with a guide-way; a support slidable on said guide way; a rotary member mounted on 20 said support; and a tool operated by said rotary member and adapted to operate upon the valve body seat.
11. In an apparatus for reseating the valve body seats of gate valves of valve barrels, the combination of a base having supporting arms resting upon and adapted to be clamped upon the barrel flange, and provided with a vertical body portion formed with a vertical slide-way having an 30 under-cut fixed guide at one edge; an under-cut beveled adjusting gib at the other edge of the slide way; a support comprising a vertical slide in said slide-way, upper bearing brackets having respectively a vertical upper bearing bore, and lower vertical and horizontal bearing brackets having respectively vertical and horizontal upper and lower bearing bores; a rotary sleeve in said vertical bearing bores; a rotary feed shaft in said 40 sleeve; means for driving said sleeve; a supporting gear having a journal shaft in said lower horizontal bore; a feed screw disposed diametrically of said supporting gear; a tool carrier disposed across said supporting gear and movable by said screw; gear means operatively connecting said supporting gear and sleeve; and gear means operatively connecting said shaft and feed screw.
12. In combination of an H-shaped base having supporting arms and provided with a vertical body portion formed with a vertical slide-way; a support comprising a slide in said slide-way, and having respectively vertical bearing bores, and a lower horizontal bearing bore; a rotary sleeve in said vertical bearing bores; a rotary feed shaft in said sleeve; a journal shaft in said lower horizontal bore; a supporting gear on said journal shaft; a feed screw on said supporting 50 gear; a tool carrier on said supporting gear and movable by said screw; means operatively connecting said supporting gear and sleeve; and gear means operatively connecting said shaft and feed screw.
13. In an apparatus for reseating the valve body seats of a gate valve still connected to the pipe line, but from the valve barrel of which the valve cap and valve stem have been removed, the combination of an H-shaped base having supporting arms resting upon and adapted to be clamped upon the flange of the valve barrel, and provided with a vertical body portion 60 formed with a flat vertical slide-way having an under-cut beveled fixed guide at one edge; an under-cut beveled adjusting gib at the other edge of the slide way; a headed bolt holding said gib in place; a support comprising a vertical, beveled slide in said slide-way, upper bearing brackets having respectively vertical and horizontal upper bearing bores, and lower vertical and horizontal bearing brackets having respectively vertical and horizontal upper and lower bearing bores; a rotary sleeve in said vertical bearing bores; a rotary feed shaft in said sleeve; a drive shaft in said upper horizontal bore and operatively connected 70 with said sleeve; a supporting gear having a journal shaft in said lower horizontal bore; a feed screw disposed diametrically of said supporting gear; a tool carrier disposed across said supporting gear and movable by said screw; gear means operatively connecting said supporting gear and sleeve; and gear means operatively connecting said shaft and feed screw.
14. In combination, a tool carrier provided with a tool-seat opening provided with a screw receiving recess; a tool block in said opening and provided with interrupted threads, and with a tool-receiving recess forming a rear shoulder; and an adjusting screw in said screw-receiving recess and engaging said threads.
15. In combination, a support; a supporting member mounted on said support; means for driving said supporting member; a tool carrier on said member and provided with a tool-seat opening provided with a screw receiving recess; a tool block in said opening and provided with a tool-receiving recess; and with interrupted threads; a tool in said recess; and an adjusting screw in said screw-receiving recess and engaging said threads.
16. In an apparatus for reseating valve body seats, the combination of a support; a supporting member mounted on said support; means for rotating said member; a tool carrier movably disposed across said supporting member; a tool head carried on said tool carrier and provided with a diag-

- onal tool-seat opening provided in one wall thereof with a longitudinal screw receiving recess; a tool block in said opening and provided with a tool-receiving recess, and 5 with interrupted threads; a tool in said recess; a clamping screw in said head and pressing the tool against said block; and an adjusting-screw receiving recess and engaging said threads.
- 10 17. In combination, an adjustable support adapted to be secured to the flange of a valve barrel; a rotary sleeve and a rotary feed shaft on said support; means for adjustably locking said sleeve and shaft together; means 15 for rotating said sleeve; a supporting gear mounted on said support; a feed screw disposed diametrically of said supporting gear; a tool carrier disposed diametrically across said supporting gear and movable by 20 said screw; a tool head carried on the end of said tool carrier and provided with a diagonal tool-seat opening provided in one wall thereof with a longitudinal screw receiving recess; a tool block in said opening and provided with a tool-receiving recess, 25 and with interrupted threads; a tool in said recess; a clamping screw in said head and pressing the tool against said block; an adjusting screw in said screw-receiving recess and engaging said threads; gear means operatively connecting said supporting gear and sleeve; and gear means operatively connecting said shaft and feed screw said means having such ratio that said feed screw is caused to feed when the lever and 30 shaft are locked together and rotated forwardly.
